INDICATOR FOR THE COOLING SYSTEM OF AUTOMOBILES

Howard E. Christie and Kibbey W. Couse,
Bronx, N. Y.

Application July 23, 1928. Serial No. 294,785

13 Claims. (Cl. 265—45)

This invention relates to an indicator for the cooling system of automobiles, being in the nature of an improvement upon the structure shown and described in pending application 5 Serial No. 197,190, filed June 7th, 1927.

A particular object of the present improvement is to provide a simplified and efficient indicator which will be thoroughly practical in operation and which may be manufactured at 10 low cost.

Other objects and aims of the invention, more or less specific than those referred to above, will be in part obvious and in part pointed out in the course of the following description of the 15 elements, combinations, arrangements of parts and applications of principles constituting the invention; and the scope of protection contemplated will be indicated in the appended claims.

In the accompanying drawing which is to be 20 taken as a part of this specification, and in which we have shown merely a preferred form of embodiment of the invention, there is illustrated a vertical sectional view through an indicator constructed in accordance with this invention and showing the same as it appears in use connected with the cooling system of an 25 automobile or like engine.

Referring to the drawing for describing in 30 detail the structure illustrated therein, the reference character L indicates a part of the cooling system of an automobile engine, as for instance the flexible connecting hose or pipe which is usually employed extending between the upper part of the engine and the upper part of an 35 automobile radiator.

The indicator device shown comprises a body member G which has a vertical annular central bore 1 arranged to accommodate the hydrometer float H so that said float is free to move vertically therein.

The body G is preferably formed of metal and the interior wall surface of the bore 1 thereof is smooth and even throughout so that the float H may have uninterrupted vertical movement, 45 the float being provided with an upper set of pointed projections 2—2 thereon and a lower set of projections as 3—3 adapted to have appropriate contact with the smooth metallic surface of the bore 1 to thereby maintain the float 50 in substantially vertical alignment with the bore at all times.

Resting within an upper annular shoulder as 4 of the body G is a gasket 5 upon which rests in turn the lower end of a transparent glass tube 6. 55 The upper portion of the body continues up-

wardly about the glass tube 6 and is threaded exteriorly as at 7 at its upper end adapted to receive a metallic cap as 8 thereon, said cap carrying a gasket 9 at its interior resting in contact with the upper annular edge of the glass tube so that when the cap is screwed tightly home it will clamp the glass tube between the gaskets 5 and 9 thus completely closing both ends of the glass tube.

A suitable window as 10 is provided at one side 65 of the body through which the glass tube and its contents may be inspected at any time.

An opening as 11 is provided through the wall of the body and communicating with the interior of the hose L through suitable coupling means 70 as 12, so that fluid from within the hose may move into the interior of the bore for floating the hydrometer, and backwardly into the hose as hereinafter referred to.

Within the bore 1 is arranged a piston valve 75 13 wherewith the opening 11 may be opened or closed at will.

As a convenient means of manipulating the valve a stem as 14 is provided thereon extending downwardly to a point of access beneath the 80 lower end of the body, being there provided with a suitable handle as 15 by which the valve may be slid up and down within the bore at the will of the operator.

Adjacent the gasket 5 an opening as 16 is provided into the interior of the body, and glass tube 6. This opening is controlled by a manually operable valve 17 which is normally closed. A spring 18 is arranged for holding the valve normally outwardly against its seat 19; and a finger 90 piece 20 projects outwardly from the valve, being of less diameter than the opening 21 through which it projects, so that when the valve is pressed inwardly by an operator's finger against the outer end of part 20, air from within the 95 body G may move freely outwardly through the openings 16 and 21 to facilitate the entry of fluid from the hose L.

When the fluid moving inwardly from the hose and rising within the body has reached a level 100 shutting off the opening 16 its rise within the glass tube will be halted, owing to the sealed character of said tube. The location of the opening 16 will thus automatically determine the working or "reading" level of the fluid within 105 the device.

A small quantity of the fluid may perhaps flow through the openings 16 and 21, and this will serve as a positive informant to the operator that the maximum or reading level of the fluid 110

has been attained, whereupon he will release the valve 20 and proceed to read the hydrometer which will be at that time floating in a readable position upon the fluid.

- 5 By moving the valve 13 to close the opening 11 the fluid within the body G will be permanently retained. If the fluid within the body is stale or, for any reason not such as to admit of a proper reading, it may be renewed by simply 10 pumping up and down by means of the valve and its handle until the fluid has been exchanged by a new supply from the hose, it being here noted that with each downward movement of the valve a partial vacuum will be created above the level 15 within the glass tube and cause a small quantity of fluid to move inwardly from the hose, as soon as the opening 11 is uncovered, and that likewise each upward movement of the valve will tend to produce compression above the level and 20 thereby cause a small quantity of fluid to move outwardly through the opening 11.

The body G is sufficiently elongated below the opening 11 so that the valve is capable of considerable piston movement below the level of the opening 11, thus to facilitate the in-flow and discharge of appreciable quantities of fluid upon occasion.

Or, if desired, the fluid within the body G may be entirely removed at any time, simply by unscrewing the cover or cap 8 and either drawing off the fluid or tipping the body so that the fluid will flow out through the open upper end. The valve will, of course, in this event, be positioned to close the opening 11. In some cases a thorough flushing of the interior of the casing may be brought about by simply moving the piston downwardly to uncover the opening 11 so that the water from the cooling system will rush into and overflow the casing. This rush of fluid may 40 be stopped at any time by simply returning the piston to close the opening 11.

Here it may be mentioned that any surplus fluid accumulated within the casing at any time, either while the cover 9 is on or off, may be withdrawn by simply holding the valve 17 open until the surplus fluid has dribbled off through the passage 21.

If the valve 17 be held open to permit discharge of fluid at a time while the valve 13 is in open position the passage of fluid through the casing will result in renewal of the fluid contents of the casing at any time.

The seat 19 for the valve member 17 may be provided in any appropriate manner but for convenience and efficiency it is preferably made up as a part of a separately formed member 22 of molded soft rubber which is held in position by being engaged tightly about an annular rib 23 provided to receive it upon the body.

60 As many changes could be made in this construction without departing from the scope of the invention, as defined in the following claims, it is intended that all matter contained in the above description or shown in the accompanying drawing, shall be interpreted as illustrative only and not in a limiting sense.

Having thus described our invention, what we claim as new and desire to secure by Letters Patent is:

- 70 1. An indicator device for a cooling system of the type set forth, said indicator device comprising a hydrometer float having a stem portion, a hollow casing for containing said float, said casing having a transparent portion through which the stem portion of the float is visible, means by

which the casing may be operatively connected with the cooling system, a piston, the casing being shaped to constitute a cylinder within which the piston is freely slideable and having an opening through the side wall thereof through which cooling fluid from the system may move between the system and the casing, and the sliding movements of the piston serving to cover and uncover said opening. 80

2. An indicator device for a cooling system of the type set forth, said indicator device comprising a hydrometer float, a hollow casing for containing said float, means by which the casing may be operatively connected with the cooling system, said means providing an opening through which cooling fluid from the system may move between the system and the casing, and a piston mounted to slide within the casing for producing movement of the fluid back and forth through said opening. 85

15 3. An indicator device for a cooling system of the type set forth, said indicator device comprising a hydrometer float, a hollow casing for containing said float, means by which the casing may be operatively connected with the cooling system, said means providing an opening through which cooling fluid from the system may move between the system and the casing, and a piston mounted to slide within the casing for producing movement of the fluid back and forth through said opening. 90

20

3. An indicator device for a cooling system of the type set forth, said indicator device comprising a hydrometer float, a hollow casing for containing said float, means by which the casing may be operatively connected with the cooling system, said means providing an opening through which cooling fluid from the system may move between the system and the casing, and a piston mounted to slide within the casing for producing movement of the fluid back and forth through said opening. 95

25

4. An indicator device for a cooling system of the type set forth, said indicator device comprising a hydrometer float, a hollow casing for containing said float, means by which the casing may be operatively connected with the cooling system, said means providing an opening through which cooling fluid from the system may move between the system and the casing, the upper portion of the casing being air tight and there being an opening communicating with the interior of the casing at approximately the desired fluid level, said opening extending downwardly from said level to there being an overflow by gravity for fluid from within the casing. 100

30

4. An indicator device for a cooling system of the type set forth, said indicator device comprising a hydrometer float, a hollow casing for containing said float, means by which the casing may be operatively connected with the cooling system, said means providing an opening through which cooling fluid from the system may move between the system and the casing, the upper portion of the casing being air tight and there being an opening communicating with the interior of the casing at approximately the desired fluid level, said opening extending downwardly from said level to there being an overflow by gravity for fluid from within the casing. 105

35

5. An indicator device for a cooling system of the type set forth, said indicator device comprising a hydrometer float, a hollow casing for containing said float, means by which the casing may be operatively connected with the cooling system, said means providing an opening through which cooling fluid from the system may move between the system and the casing, the upper portion of the casing being air tight and there being an opening communicating with the interior of the casing at approximately the desired fluid level, said opening extending from said level into communication with the outer atmosphere so as to constitute an overflow by gravity for fluid from within the casing, together with a manually operable valve controlling said overflow opening. 110

40

5. An indicator device for a cooling system of the type set forth, said indicator device comprising a hydrometer float, a hollow casing for containing said float, means by which the casing may be operatively connected with the cooling system, said means providing an opening through which cooling fluid from the system may move between the system and the casing, the upper portion of the casing being air tight and there being an opening communicating with the interior of the casing at approximately the desired fluid level, said opening extending from said level into communication with the outer atmosphere so as to constitute an overflow by gravity for fluid from within the casing, together with a manually operable valve controlling said overflow opening. 115

45

6. An indicator device for a cooling system of the type set forth, said indicator device comprising a hydrometer float, a hollow casing for containing said float, means by which the casing may be operatively connected with the cooling system, said means providing an opening through which cooling fluid from the system may move between the system and the casing, the upper portion of the casing being air tight and there being an opening communicating with the interior of the casing at approximately the desired fluid level, said opening extending from said level into communication with the outer atmosphere so as to constitute an overflow by gravity for fluid from within the casing, together with a manually operable valve controlling said overflow opening. 120

50

6. An indicator device for a cooling system of the type set forth, said indicator device comprising a hydrometer float, a hollow casing for containing said float, means by which the casing may be operatively connected with the cooling system, said means providing an opening through which cooling fluid from the system may move between the system and the casing, the upper portion of the casing being air tight and there being an opening communicating with the interior of the casing at approximately the desired fluid level, said opening extending from said level into communication with the outer atmosphere so as to constitute an overflow by gravity for fluid from within the casing, together with a manually operable valve controlling said overflow opening. 125

55

6. An indicator device for a cooling system of the type set forth, said indicator device comprising a hydrometer float, a hollow casing for containing said float, means by which the casing may be operatively connected with the cooling system, said means providing an opening through which cooling fluid from the system may move between the system and the casing, the upper portion of the casing being air tight and there being an opening communicating with the interior of the casing at approximately the desired fluid level, said opening extending from said level into communication with the outer atmosphere so as to constitute an overflow by gravity for fluid from within the casing, together with a manually operable valve controlling said overflow opening. 130

60

6. An indicator device for a cooling system of the type set forth, said indicator device comprising a hydrometer float, a hollow casing for containing said float, means by which the casing may be operatively connected with the cooling system, said means providing an opening through which cooling fluid from the system may move between the system and the casing, the upper portion of the casing being air tight and there being an opening communicating with the interior of the casing at approximately the desired fluid level, said opening extending from said level into communication with the outer atmosphere so as to constitute an overflow by gravity for fluid from within the casing, together with a manually operable valve controlling said overflow opening. 135

65

6. An indicator device for a cooling system of the type set forth, said indicator device comprising a hydrometer float, a hollow casing for containing said float, means by which the casing may be operatively connected with the cooling system, said means providing an opening through which cooling fluid from the system may move between the system and the casing, the upper portion of the casing being air tight and there being an opening communicating with the interior of the casing at approximately the desired fluid level, said opening extending from said level into communication with the outer atmosphere so as to constitute an overflow by gravity for fluid from within the casing, together with a manually operable valve controlling said overflow opening. 140

70

6. An indicator device for a cooling system of the type set forth, said indicator device comprising a hydrometer float, a hollow casing for containing said float, means by which the casing may be operatively connected with the cooling system, said means providing an opening through which cooling fluid from the system may move between the system and the casing, the upper portion of the casing being air tight and there being an opening communicating with the interior of the casing at approximately the desired fluid level, said opening extending from said level into communication with the outer atmosphere so as to constitute an overflow by gravity for fluid from within the casing, together with a manually operable valve controlling said overflow opening. 145

75

6. An indicator device for a cooling system of the type set forth, said indicator device comprising a hydrometer float, a hollow casing for containing said float, means by which the casing may be operatively connected with the cooling system, said means providing an opening through which cooling fluid from the system may move between the system and the casing, the upper portion of the casing being air tight and there being an opening communicating with the interior of the casing at approximately the desired fluid level, said opening extending from said level into communication with the outer atmosphere so as to constitute an overflow by gravity for fluid from within the casing, together with a manually operable valve controlling said overflow opening. 150

- the casing, together with a valve for controlling said overflow opening said valve including a part holding it normally closed but being yieldable by manual pressure to open the valve.
5. 7. An indicator device for a cooling system of the type set forth said indicator device comprising a hydrometer float, a hollow casing for containing said float, means by which the casing may be operatively connected with the cooling system, a piston, the casing being shaped to constitute a cylinder within which the piston is freely slideable and having an opening thereto controlled by said piston said opening providing for communication between the system and the interior of the casing, and said piston constituting a bottom wall for said casing beneath the hydrometer float. 80
8. An indicator device for a cooling system of the type set forth, said indicator device comprising a cylindrical metallic body portion and a cylindrical upper portion of glass, a hydrometer float positioned within said body portion and projecting upwardly therefrom into said glass portion, the body portion having an opening therethrough through which fluid from the cooling system may enter said body portion to float the hydrometer float, the lower end of the glass portion being approximately at the desired fluid level, and the body portion having an opening communicating with the interior of the device at approximately said level and extending from said level so as to constitute an overflow for fluid from within the device. 90
9. An indicator device for a cooling system of the type set forth, said indicator device comprising a cylindrical metallic body portion and a cylindrical upper portion of glass, a hydrometer float positioned within said body portion and projecting upwardly therefrom into said glass portion, the body portion having an opening therethrough through which fluid from the cooling system may enter said body portion to float the hydrometer float, the lower end of the glass portion being approximately at the desired fluid level, 95
- 40 the body portion having an opening therethrough communicating with the interior of said glass portion at approximately said level and extending downwardly from said level into communication with the outer atmosphere to thereby constitute an overflow for fluid from within the device, the upper end of said glass portion being air tight, and a manually operable valve for controlling said overflow opening. 100
10. An indicator device for a cooling system of the type set forth, said indicator device comprising a hollow base part having a transparent tube extending therefrom and forming therewith a float chamber, a hydrometer float arranged 105
- within said chamber having at least its readable part positioned within said tube, said chamber having an opening formed through the wall thereof communicating with the interior thereof at approximately the desired artificial fluid level, and a manually operable valve arranged in said opening for controlling said opening, said opening and said valve constituting means co-operative in the structure to create an artificial fluid level within the chamber for the operation of the hydrometer float. 110
11. An indicator device for a cooling system of the type set forth, said indicator device comprising a hollow base part having a transparent tube extending therefrom and forming therewith a float chamber, a hydrometer float arranged within said chamber having at least its readable part positioned within said tube, said chamber having an opening formed through the wall thereof communicating with the interior thereof at approximately the desired artificial fluid level, a manually operable valve arranged in said opening for controlling said opening, said opening and said valve constituting means co-operative in the structure to create an artificial fluid level within the chamber for the operation of the hydrometer float, and said base part having a portion extending therefrom constituting a shield about the transparent tube but formed with a window therethrough through which the hydrometer float is visible within the tube. 115
12. An indicator device for a cooling system of the type set forth, said indicator device comprising a hydrometer float, a hollow casing for containing said float, said casing having a transparent portion through which the float is visible, means by which the casing may be operatively connected with the cooling system, a piston, the casing being shaped to constitute a cylinder within which the piston is freely slideable and having an opening through the side wall thereof through which cooling fluid from the system may move between the system and the casing, and the piston being slideable to cover and uncover said opening. 120
13. An indicator device for a cooling system of the type set forth, said indicator device comprising a hydrometer float, a hollow casing for containing said hydrometer float, means by which said casing may be operatively connected with the cooling system, said means providing an opening through which cooling fluid from the system may move between the system and the casing, and manually operable means to control said opening and to cause movement of fluid back and forth through said opening. 125
